UNITED STATES PATENT OFFICE.

MARIE PUISSANT, OF ST.-GRATIEN, NEAR PARIS, FRANCE.

PUBLICITY APPARATUS.

1,218,699.

Specification of Letters Patent. Patented Mar. 13, 1917.

Application filed August 1, 1914. Serial No. 854,462.

To all whom it may concern:

Be it known that I, MARIE PUISSANT, a citizen of France, residing at Rue de l'Orme at St.-Gratien, near Paris, Seine - et - Oise, France, have invented certain new and useful Improvements in Publicity Apparatus; and I do hereby declare that the following is a full, clear, and exact description of the same.

10 My invention relates particularly to advertising mediums of the type which are suitable for use during the day as well as at night.

15 The invention may be said briefly to consist of a series of ribbons arranged side by side and bearing advertising matter, means preventing oblique winding of the ribbons and means for operating each ribbon independently of the other ribbons for the pur-

20 poses of enabling such ribbon to co-act with the other ribbons in the composition of an advertisement; and the particular construction and arrangement of parts hereinafter described and pointed out in the claims.

25 For full comprehension, however, of my invention reference must be had to the accompanying drawings forming a part of this specification, in which similar reference characters indicate the same parts, and

30 wherein:

Figure 1 is a front elevation of an advertisement frame built according to this invention;

Fig. 2 is a cross-section on a larger scale 35 taken on lines 2—2 of Fig. 1;

Fig. 3 is a back view of the front part of the frame;

Fig. 4 is a detail bottom plan view of a 40 pair of rollers and the means for rotatably mounting the same;

Fig. 5 is a detail elevation of one of the rollers;

Fig. 6 is an elevation of one of the friction rings adapted to be inserted between the 45 ends of each roller and the adjacent bracket;

Fig. 7 is a side elevation of the means for detachably fastening the end of each ribbon upon its respective roller;

Figs. 8 and 9 illustrate a unitary advertising device constructed according to my invention, Fig. 8 being a front elevation and Fig. 9 a sectional view;

Fig. 10 is an end elevation of the means illustrated in Fig. 7.

55 The casing of my improved device consists of two sheet-metal members A A' of similar cross-section hingedly connected at

their lower side-edges as at c and detachably connected at their opposite side edges by a catch d or any other suitable means, such 60 casing members presenting tubular portions a and a' and the portion of each member intermediate of these tubular portions being offset outwardly as at a² to accommodate preferably two parallel lengths of plate 65 glass b extending through the length of the casing and being retained in place by comparatively small turned-in flanges at each end thereof. The lengths of glass are spaced slightly apart to receive the advertisement 70 bearing ribbons to be hereinafter further al- luded to, and which are adapted to be inde- 75 pendently fed therebetween. If desired the glass may be placed outside of the casing and any other translucent or transparent mate- 80 rial may be substituted therefor. This par- ticular arrangement owing to the small space between the glass plates and the flat con- 85 tiguous surface thereof, prevents wrinkling of the ribbons; while the relative spacing of the ribbons close to each other affords ample scope for the arrangement of the letters or characters in proper position relatively to each other.

Other advantageous features of this de- 85 vice are that the specific construction of the casing prevents dust working its way into the interior, and makes the sign partic- 90 ularly adaptable for use at night as no parts of the mechanism intercept the rays of light from the lighting source and consequently 95 no shadows are cast on the lettering as is so frequently experienced in internally illuminated signs.

Each offset a² is provided with a plurality 95 of apertures or windows of preferably rec- 100 tangular form and equal in number to the maximum number of letters or characters to be employed, the various strips separating each aperture from the adjoining apertures merely serving to frame the letters or char- 105 acters composing the advertisement and to hide the side edge of the ribbons and may be reduced to any width required. If de- sired one large aperture or window may be 110 substituted for the plurality of smaller ap- 115 ertures and the strips separating the letters or characters and hiding the side edges of the ribbons may be painted upon the glass without departing from the spirit of my in- vention.

As already stated the advertising matter is carried by a series of paper ribbons or tissue bands f, the ends of which are wound

on rollers *k* located in the tubular portions of the casing members. These ribbons or bands are all located in the same vertical plane and pass between the lengths of 5 glass *b* opposite their respective apertures and each is operated independently of the other for the purpose of bringing any desired letter or character opposite its respective aperture. The rollers *k* are divided 10 into two spaced and opposite series, each corresponding pair of rollers having one of the ribbons wound thereon.

Each roller is constituted by a tube, one end of which has attached thereto a wheel 15 *k'* of comparatively large diameter having a milled edge to facilitate rotation thereof, the length of each tube being equal to the width of each ribbon which is connected thereto. In order to rotate the rollers without 20 disturbing the casing members, the casing member *A'* is provided with a series of slots opposite the milled wheels through which access may be had thereto.

Up to the present time considerable difficulty has been experienced in signs of this 25 type from the fact that the ribbons have had a tendency to wind obliquely to the normal direction of travel which consequently marred the artistic appearance of 30 the advertisement. In order to overcome this defect in the present construction each series of rolls is mounted upon a rod *g* extending through the length of the casing and journaled in a series of brackets *h* 35 spaced uniformly apart and secured to the casing member *A* in the tubular portions thereof, displacement of the rods being prevented by nuts *i* on the ends thereof. The brackets *h* are spaced just far enough apart 40 to accommodate the rollers *k*, a small friction ring consisting of a split metallic washer, one end of which is turned down on the side to form a spring (see Fig. 6), being inserted between each milled wheel 45 and the flange of the bracket immediately adjoining, to prevent the rollers unwinding under the tension of the ribbons which would have the undesirable effect of disarranging the letters or characters from their 50 proper respective positions after having been arranged. This particular construction provides a space between the flange of the bracket at the end of the roller opposite to the milled wheel and the wheel itself 55 which is equal to the width of each ribbon so that it is impossible for the ribbon to wind obliquely as the flange acts as a guide on one side and the milled wheel on the other.

60 When the ribbon becomes worn it is desirable to substitute a new ribbon without dismantling the other ribbons, to this end each ribbon is detachably mounted on a pair

of the rollers by winding its ends once or twice around the same and embracing the 65 whole by an elastic metal piece of open tubular cross-section.

The casing may be provided with suspension hooks *e* or any other suitable means for mounting the same in place and may be 70 adorned with various ornaments to add to the attractiveness of the advertisement.

In order to change an advertisement the rollers *k* are rotated by means of the milled wheels *k'* access to which is obtained 75 through the slots in the casing members. When the required letter on one ribbon appears opposite its respective aperture the adjoining ribbon is operated and so on until the composition of the advertisement is complete. Whenever the mechanism gets out of order the front of the casing *A'* is swung 80 open exposing all the parts to view and enabling the operator to see at a glance where the trouble is located.

85 If desired my improved advertising medium may comprise a number of lines located one above the other which vary in length or height to meet different requirements, the general arrangement in each case, however being the same.

If desired the ribbons may be mounted upon a lamp bracket in which case the ends of the casing would be turned in and the upper side edge thereof provided with a 95 rearward extension thus presenting an enclosure for the light, the rearward extension also serving as a reflector plate.

What I claim is as follows:

An advertising medium consisting of a 100 pair of rectangular casing members rigidly connected at their lower side edges and detachably connected at their opposite side edges said casing members presenting a tubular portion in close proximity to each 105 edge thereof extending throughout the length of the same, rollers mounted in each of said tubular portions, each of said members being offset outwardly and having apertures therein, a pair of lengths of plate 110 glass mounted within said offset portions, a ribbon bearing advertising matter and having its opposite ends detachably mounted upon said rollers, means for rotating each of said rollers said means consisting of a 115 wheel rigidly mounted upon one end of said rollers and having a milled edge and a slot in one of said casing members adjacent each wheel for permitting access thereto.

120 In testimony whereof I have signed my name to this specification in the presence of two witnesses.

MARIE PUISSANT.
